BAND BRAKE

Andrew Gordon Wilson and Albert A. Miller, Coventry, England, assignors to Self-Changing Gear Company Limited, Coventry, England

Application February 26, 1947, Serial No. 730,918
In Great Britain September 28, 1945

8 Claims. (Cl. 188—77)

1

This invention relates to band brakes of the type comprising a brake drum lapped by at least three gapped brake bands disposed side by side, and wherein the brake operating force is applied to one end of one of the bands (hereinafter called the primary band) and the reaction end thereof being coupled to the application ends of the other bands (referred to hereinafter as secondary bands).

The object of the invention is to provide, in a band brake of the type described, a balanced brake wherein reaction forces are prevented from acting transversely of the break drum axis.

The invention consists in a band brake of the type indicated, characterized in this that the reaction ends of the secondary bands are each connected to means transmitting the reaction equally and in the same sense to said bands at the opposite side of the axis of the brake drum in such a manner that the moments of the forces acting about the drum axis on the application of the brake are substantially balanced.

The invention also consists in a band brake as set forth in the preceding paragraphs, wherein the balancing means comprise oppositely disposed equalizing levers interconnected at their inner ends and carrying at their outer ends respectively reaction and balancing links, the said links being preferably also each connected to its lever through a slip-friction grip which may be located on the side of the lever fulcrum remote from the link coupling.

The invention further includes a band brake according to the preceding paragraph wherein the force application end of the primary band is connected by a tie link to a pivoted lever which is located on the same side of the drum as that on which the reaction link is situated and to which the braking force is applied.

An alternative means of brake actuation according to the invention and with the same objects in view, comprises a rod preferably operated by a piston actuated by hydraulic or fluid pressure acting on the fulcrum of one of a pair of equalizing levers disposed on the side of the brake band remote from those already referred to, the outer ends of the equalizing levers being connected through links to the primary band on opposite sides of the drum axis, the lever engaged by the rod being free from connection with the frame or casing while the other equalizing lever is fulcrummed to the casing, the inner ends of the levers being linked or otherwise connected together in the same manner as in the case of the equalizing levers originally referred to.

2

Referring to the accompanying drawings:

Figure 1 is an elevation partly in section of a brake constructed in accordance with the invention;

Figure 2 is an end view of the brake mechanism taken from inside the casing in the direction of the arrows 2—2 in Figure 1;

Figure 3 is a section of the guide plate for the brake bands taken on the line 3—3 in Figure 1.

10 In carrying the invention into effect according to one mode, described by way of example, a brake drum 1 which normally rotates in a counterclockwise direction is disposed within a casing 2 having a cover 3 as shown in Figure 1. 15 The drum is encircled by three gapped or circumferentially divided brake bands lined with any usual frictional material and disposed in side by side relationship, with the band gaps all lying to the left-hand side of the vertical diametrical plane of the drum as viewed in Figure 1. The primary band 4 to which the braking force is applied is located intermediate the secondary bands 5 and 6 and has secured to one end thereof a pair of hook members 7 to which the braking 20 force is applied. The opposite (reaction) end of the primary band 4 is secured to the two adjacent ends of the secondary bands 5 and 6 in any convenient manner but in the present instance the primary and secondary bands are integral, that is to say they are formed by cutting from the same piece of material, the common portion representing the join between the two bands being indicated at 8. The gap in the primary band is shown at 9 and the gaps in the secondary bands at 10 Fig. 2.

25 The reaction ends of the secondary bands are each provided with a pair of spaced hook lugs 11 and 11a, and similarly spaced eye lugs 12 are secured to the secondary bands in symmetrical relation on the opposite side of the vertical centre line of the drum.

30 The balancing mechanism is disposed in the casing beneath the brake drum and comprises essentially a pair of levers of the first order having their fulcrums on the casing and being connected for movement in unison in opposite senses, the outer ends of the levers being connected by links to the lugs 11, 11a and 12 on the secondary bands. Considering the left-hand side of the casing in Figure 1 (in conjunction with Fig. 2), spaced supports 13 and 14 secured to the bottom of the casing 1 constitute fulcrums for a pair of oppositely disposed levers 15 and 16. Each lever 35 comprises a pair of similar plates riveted or welded together in spaced relation, the plates

lying one on either side of the fulcrum support 13, 14. Similar spaced fulcrum supports are disposed symmetrically on the right-hand side of the casing, one of which is shown at 18 carrying a lever 19. The inner ends of the levers 16 and 19 are recessed to receive a pin 20. It will be understood that there is a similar lever behind lever 19 which is similarly mounted on a fulcrum support behind lever 19 and is similarly interconnected with the lever 15 behind lever 16.

A reaction link 21 is pivoted at 22 to the outer end of lever 16 and carries at its upper end a pin 23 which engages within the hook slot formed in the lug 11a which as previously described is mounted on the free or reaction end of the secondary brake band 6. The reaction link 21 is of bell-crank form having an arm 24 which is curved and cut away as shown in Figure 1 to clear the fulcrum 14.

The extremity of the arm 24 is formed with an enlargement 25 having an aperture or slot and lying within the space between the two plates which constitute the lever 16. Within the eye or slot is located a slip friction device 26 consisting of a short length of helical spring which is compressed within the side plates aforesaid.

The lever 15 (see Fig. 2) is similarly pivoted at 22a to a reaction link 27 carrying at its upper end a pin 28 which engages in the hook slot of the second lug 11 secured to the reaction end of the secondary brake band 5.

The balancing lever 19, which as previously described is interconnected with balancing lever 16, is connected to the lug 12 on the secondary brake band 6 by a balancing link 29 pivoted to the lever at 30 and having a bell crank arm 31 with an apertured enlargement 32 accommodating a slip friction device 33, the arrangement being generally similar to that of the reaction link 21. It will be understood that there is a second balancing lever, similar to lever 19, which is interconnected with balancing lever 15, and this second lever is connected to the secondary brake band 5 by a balancing link and lug which are similar in all respects to the link 29 and lug 12 just described.

Application of the braking force is effected by any convenient means such as a hydraulic or pneumatic cylinder (not shown) acting upon a piston rod 34 pivoted at 35 to a link 36 composed of parallel spaced plates, which link is pivotally connected by means of a pin 37 to the reaction links 21 and 27 and by means of a pin 38 to the tie link 39 which is curved in elevation and carries at its upper end a pin 40 which engages in the hook lugs 1 attached to the end of the primary brake band 4.

Means are provided for guiding the upper parts of the brake bands in their limited circumferential motions, and comprise a pair of plates 41 and 42 located in spaced relationship with regard to the vertical diametric plane of the drum. Each plate extends laterally across the three bands as shown in Figure 3, the plate 41 having an outwardly projecting rib 43 guided between a pair of fins 44 extending inwardly from the cover 3 of the brake casing. The plate 41 is riveted to the outer brake bands 5 and 6 and is provided with a recess 45 which receives the inner or primary band 4. The plate 42 is similarly arranged and constructed. Plates 46 and 47 connecting the secondary brake bands and affording a guide for the primary band are preferably provided in the lower part of the brake casing. These plates are similar to the plate 41 and serve also to take

the weight of the primary band when the brake is in the "off" position.

The duty of supporting the weight of the brake bands collectively when no braking force is being applied comes on the reaction and balancing links, e. g. links 21 and 29. It will be appreciated from a consideration of Figure 1 of the drawing that when the lower part of the brake band as a whole has dropped to the requisite clearance from the drum surface, the inner arms of the equalizing levers 16 and 19 will have risen by such an amount that the slip friction members 26 and 33 will have reached the top of the apertures in the reaction and balancing links. As no further movement of the levers can take place without displacement of the friction grips, the weight of the bands is thus adequately supported. The diameter of the apertures which embrace the friction devices is chosen so that the amount which the lower part of the band can drop when the brake is released is such as to produce approximately an equal clearance between the top portion of the band and the drum. It will of course be understood that although the friction afforded by the devices in question is adequate to support the weight of the brake bands, it will not be sufficient to resist displacement in the opposite direction when the brake lining wears, and the brake application force draws the band closer to the drum. The friction devices are self-adjusting and will accordingly become progressively displaced upwardly relative to the levers as the brake lining wears, thus maintaining a constant clearance relative to the drum when the brake is released irrespective of wear.

Upon application of the braking force through the piston rod 34, the link 36 is rotated in a counterclockwise direction about the pivot 37 and the tie link 39 is pulled down, thus transmitting a pull to the application end of the primary brake band 4. This tends to cause a consequential displacement in the same direction to the reaction end of the primary band, but as this end is coupled to the application ends of the secondary bands 5 and 6, the braking force is transmitted to the said application ends of the secondary bands.

While the piston rod is causing a pull on the tie link 39, the reaction links (e. g. 21) thrust upwardly against the lugs 11, 11a on the secondary brake bands. In this operation the friction devices 26 and 33 are displaced upwardly (as wear occurs) on their levers after the play permitted by the apertures has been taken up. Through the action of the equalizing levers the corresponding balancing links (e. g. 29) support and thrust upon the secondary brake bands on the opposite side of the drum, thereby relieving the drum of one-sided load by affording a balancing moment on that side of the drum opposite that on which the brake applying force acts. Upon relief of the braking pressure, the stresses are released and the bands are released from the drum, the reaction and balancing links being stabilized by the engagement of the opposite ends of the apertures in the crank arms of the links surrounding the friction devices. The stresses imposed on the bands by their contraction upon the brake drum will normally be adequate to expand the bands when the pressure is relaxed. If desired, however, an auxiliary spring or springs may be provided between the band extremities for the purpose of opening the gaps when the application force is released.

It is to be understood that for conditions of

balance, the line of action of the piston rod 34 should pass approximately through the pivot connections (e. g. 22) between the reaction links and the equalizing levers and also through the fulcrum of the equalizing lever. In addition the line of pull of the tie link 39 should pass through or adjacent to the connection 23.

Whilst in the example previously given there is a single primary band in combination with two secondary bands, combinations of more than three bands are readily provided by coupling the reaction ends of one or both of the secondary bands to the application end or ends of an additional band or bands in a similar manner to that in which the reaction end of the primary band is coupled to the application ends of the secondary bands, while the reaction ends of the additional bands have reaction links and balancing links coupled by equalizing levers after the manner of the previous example. Thus the braking may be transmitted in series from band to band.

We claim:

1. A band brake comprising a brake drum, brake band means including at least a primary gapped band and two secondary gapped bands disposed side by side around said drum, means for applying the brake operating force to one end of the primary band with the reaction end thereof coupled to the application ends of the secondary bands, equalizing lever means connected to the reaction ends of the secondary bands for transmitting the reaction equally and in the same sense to said secondary bands at the opposite side of a diametric plane of the brake drum in such a manner that the moments of the forces acting about the drum axis on the application of the brake are substantially balanced, and slip-friction means included in the connections between the secondary bands and their equalizing lever means arranged so that when the bands are in the off position they are supported with a substantially constant clearance irrespective of wear.

2. A band brake comprising a brake drum, brake band means including at least a primary gapped band and two secondary gapped bands disposed side by side around said drum, means for applying the brake operating force to one end of the primary band with the reaction end thereof coupled to the application ends of the secondary bands, oppositely disposed equalizing levers, fixed fulcrums for said levers, links connecting the outer ends of said equalizing levers to points on the secondary bands symmetrically disposed on opposite sides of the diametric plane of the drum for transmitting the reaction equally

and in the same sense to said secondary bands so that the moments of the forces acting about the drum axis on the application of the brake are substantially balanced, and slip-friction connections between said links and equalizing levers whereby the bands in the off position are supported with a substantially constant clearance irrespective of wear.

3. A band brake according to claim 2, wherein 10 the said slip frictional connection comprises a lost motion means such that when the braking force is relieved the bands leave the drum and are supported by the links against the frictional connection.

15 4. A band brake according to claim 3, wherein the said links have lever arms the ends of which have a combined frictional and lost motion connection with the equalizing levers.

20 5. A brake band according to claim 4, wherein 20 the said equalizing levers comprise spaced plates between which are located the slip-friction devices having a lost motion connection with arms on the links.

25 6. A band brake according to claim 2, wherein 25 the force application end of the primary band is connected by a tie link to a pivoted lever which is located on the same side of a diametric plane of the brake drum as that on which the reaction link is situated and to which the braking force is 30 applied.

35 7. A band brake according to claim 6, wherein 35 the line of application of the force is arranged to pass through or adjacent the fulcrum of the equalizing lever connected to the reaction ends of the secondary bands and also through or adjacent the connection of the reaction link with the said lever.

40 8. A band brake according to claim 7, wherein 40 the line of pull on the primary band passes through or adjacent the connection between the reaction ends of the secondary bands and the reaction link.
